Patented Nov. 28, 1916.

UNITED STATES PATENT OFFICE.

SOLOMON MAHER, OF NORTH ADAMS, MASSACHUSETTS.

ELEVATOR SAFETY-STOP.

1,206,566.

Specification of Letters Patent. Patented Nov. 28, 1916.

Application filed July 13, 1916. Serial No. 109,116.

To all whom it may concern:

Be it known that I, SOLOMON MAHER, a subject of the Sultan of Turkey, residing at North Adams, in the county of Berkshire and State of Massachusetts, have invented certain new and useful Improvements in Elevator Safety-Stops; and I do declare the following to be a full, clear, and exact description of the invention, such as will enable others skilled in the art to which it appertains to make and use the same.

This invention relates to new and useful improvements in elevators, and more particularly to elevators operated by a hoisting cable, and the primary object of the invention is to provide an elevator of this character with a safety device whereby upon breakage of the cable, the elevator will be instantly stopped.

Another object of the invention is to provide a device of this character which is easily and simply constructed, inexpensive to manufacture and one which will be very efficient in operation.

With these and numerous other objects in view the invention consists of the novel features of construction, combination and arrangement of parts which will be herein referred to and more particularly pointed out in the specification and claims.

In the accompanying drawings: Figure 1 is a side elevation of the elevator showing the support of the same partly in section; Fig. 2 is a top plan view of the elevator with the support and rack bars in horizontal section; Fig. 3 is a detail perspective of the frame in which the end of the cable holder is mounted.

In describing my invention I shall refer to the drawings in which similar reference characters designate corresponding parts throughout the several views and in which the numeral 1 designates the elevator, which is provided with a top 2 and sides 3, the sides 45 being provided with substantially U-shaped guides 4 which are adapted to engage the sides of a rack bar 5 positioned in the elevator shaft adjacent the sides of the same.

My improved safety device is attached to the top 2 of the elevator, and consists of a frame 7 which is provided with spider arms 8 secured at their lower ends to the top of the elevator, on which is preferably positioned a metal strip as clearly shown in Figs. 1 and 3 of the drawings. The flat upper portion of the frame 7 is disposed

substantially parallel with the top of the elevator and is connected therewith by a pair of upright standards 9, and said top of the frame is also provided with a central opening 10 disposed intermediate the standards.

The lower end of the hoisting cable 11 is adapted to project through the opening 10 of the top of the frame, and is secured to a cable holder 12 positioned below the top of the frame but which has secured to its lower ends a plate 13 that is apertured adjacent its ends and which is adapted to slidably engage the standards 9. The cable holder 12 is of a height less than the distance between the flat portion of the frame and the top of the elevator and consequently the same is slidably mounted on these standards within the frame. Coiled springs 14 surround the portion of the standards between the top of the frame and the plate 13. When this elevator is in operation the sliding plate 13 secured to the bottom of the cable holder will be positioned substantially as shown in Fig. 1 of the drawings, and consequently the coil springs 14 will be compressed.

Secured to the bottom of the plate 13 at a point intermediate its ends is a flat spring 15, which is provided with elongated slotted portions 16, through which the standards 9 are positioned, and the said flat spring projects outwardly through the arms of the frame 7, and has positioned above the same rollers 17 journaled on the top of the elevator. These rollers 17 are positioned adjacent the ends of the flat spring 15, and consequently when this spring is in position and the elevator is in operation it will be bowed at its central portion that is the portion between the rollers 17. These rollers 17 are 95 journaled in bearings 18 secured to the upper surface of the top of the elevator.

It will be obvious that owing to the fact that the cable holder and plate are slidably mounted within the frame, and the flat spring is secured to said plate upon vertical movement of these parts, the ends of the flat spring that project past the rollers 17 will move horizontally. Secured to these ends which are designated by the numerals 19 are 105 blocks 20, which are consequently slidable horizontally on the top of the elevator. The ends 19 of the springs are positioned in sockets in the inner sides of the blocks 20 and are held in rigid engagement therewith by 110 bolts 21.

Securely mounted on the top of the ele-

vator adjacent the sides of the same are guides 22 in which are slidably mounted bolts 23 adapted to slide freely therethrough. These bolts and guides 22 and 23 are positioned adjacent each side of the elevator at the top of the same and projecting rearwardly from the inner ends of the bolts are pairs of rods 24 which connect said bolts with the outer faces of the sliding blocks 20. Secured to the top of the elevator at a point between the inner ends of the bolts and the blocks 20 is a stationary plate 25, which is apertured so that the rods 24 are adapted to slide freely therethrough. The portions of the rods 24 between the plate 25 and the inner ends of the bolts are surrounded by coiled springs 26. These coiled springs 26 are normally compressed when the elevator is being operated and the flat spring is bowed, consequently they will exert a constant outward tension on the inner ends of the bolts 23.

As the elevator is being operated the parts of the safety device are positioned as clearly shown in Fig. 1 of the drawings, and it will be clear that the flat spring will be bowed, and its central portion will be elevated against the tension of the coiled springs 14 with the frame 7. This bowing of the spring will also draw the bolts 23 into the guides 22 and also against the pressure of the coiled springs 26, and the said bolts also disposed out of engagement with the rack bars 5 on the sides of the elevator therefor. Upon breakage of the cable 11, the flat spring from its own tension, and also actuated by the expansion of the coil springs 14 will have its flat portion forced downwardly flat against the top of the elevator, and consequently the ends of the spring will be forced outwardly thereby releasing the bolts 23, and forcing them outwardly, this movement being further actuated by the expansion of the coiled springs 26. The bolts 23 will consequently be forced into engagement with the rack bars 5 and the elevator will be instantly stopped.

The above described safety device affords a very simple and efficient means for automatically applying a stop to an elevator of this character when the hoisting cable accidentally breaks. Owing to the spring tensions above described, the safety means will immediately and instantly act and the stop mechanism will be applied without fail. This safety attachment is especially applicable for use on dumb waiters and elevators of like character, as the extreme simplicity of the construction employed, enables the

device to be economically manufactured and to be cheaply applied to elevators of this character.

I claim:

1. The combination with an elevator mounted in a shaft, a hoisting cable, rack bars secured to the opposite sides of said shaft, of a spring pressed cable holder slidably mounted on the elevator, a flat spring on the elevator connected intermediate its ends with said holder and bowed thereby, guides on the elevator adjacent its sides, bolts slidably mounted in said guides, rollers positioned above said flat spring adjacent its ends, blocks on the ends of said spring, inwardly projecting rods connecting the inner ends of said bolts with the blocks, stationary perforated plates through which the rods are adapted to slide, and coiled springs surrounding the rods between the plates and the inner ends of said bolts. 80

2. The combination with an elevator mounted in a shaft, a hoisting cable, rack bars secured to the opposite sides of said shaft, of a frame having downwardly projecting arms secured to the top of the elevator, a pair of upright standards in said frame, a plate slidably mounted in the frame on the standards, coiled springs surrounding said standards between the plate and the upper end of the frame, a cable holder secured to said plate and adapted to normally hold the same against the compression of the coiled springs, a flat spring on the elevator secured to the plate and projecting from between the arms of the frame, and bolts slidably mounted on the elevator adjacent its sides connected with the ends of said flat spring. 95

3. The combination of an elevator mounted in a shaft, a hoisting cable, rack bars secured to the opposite sides of said shaft; of a pair of upright standards on said elevator, a cable holder slidably mounted on said standards, coiled springs surrounding the standards and normally compressed by the holder when the cable is taut, a flat spring on the elevator connected with the cable holder, and bolts operated by the ends of the said spring adapted for engagement with the rack bars should the cable break. 100

In testimony whereof I have hereunto set my hand in the presence of two subscribing witnesses.

SOLOMON MAHER.
